(57) **CLAIM**

The ornamental design for a biological collection device, as shown and described.

DESCRIPTION

FIG. 1 is a front isometric view of the biological collection device.

FIG. 2 is a front view of the biological collection device.

FIG. 3 is a back view of the biological collection device.

FIG. 4 is a left side view of the biological collection device.

FIG. 5 is a right side view of the biological collection device.

FIG. 6 is a top view of the biological collection device.

FIG. 7 is a bottom view of the biological collection device.

FIG. 8 is a front isometric view of the biological collection device in an unfolded state.

FIG. 9 is a front view of the biological collection device in an unfolded state; and,

FIG. 10 is an isometric view of the biological collection device secured to a toilet with a suction cup on both sides of the toilet.

The broken lines in FIG. 10 of the toilet and suction cup are for the purpose of illustrating environment and use, and form no part of the claimed design.

The broken lines in FIGS. 8 and 9 depict fold lines and form no part of the claimed design.
